[57] ABSTRACT

An educational device or toy consists of 10 units each made up of a transparent container in which is a post having a body portion of constant cross-section throughout its length and equal in height to the container, and 10 rings disposed one upon another to surround the body portion of the post throughout its length, each container having a lid of the same colour as its post and rings, all 10 lids being of different colours and the posts being adapted to fit together end-to-end with their body portions in abutment to form a column having ten equal differently coloured sections and capable of accommodating exactly 100 rings. The 10 units can also be used singly if desired.

EDUCATIONAL DEVICE

The invention relates to educational devices.

It is an object of the invention to provide an educational device which can be used to teach numbers and basic arithmetic and at the same time provides an attractive educational plaything for children.

A device according to the invention is preferably built up from a desired number of basic units each comprising a central post consisting of or including a body portion of constant cross-section throughout its length, and ten rings which fit around the body portion to enclose it throughout its length. Several such posts may be joined together end-to-end with their body portions in abutment to form a column, a column of 10 posts being capable of receiving exactly 100 rings. The rings are preferably of 10 different colours whereby when one ring of each colour is placed round a post 10 has been counted and when 10 rings of each colour have been placed on a 10 post column 100 has been counted and appears as 10 blocks of different colours, each block representing 10 and each ring representing one.

Advantageously the basic units could be sold separately in containers which hold exactly ten rings, whereby the containers can be used as measuring devices when the units are in use. The containers would preferably be made from a transparent synthetic plastics material.

An embodiment of the invention will now be described, by way of example only, with reference to the accompanying drawings, in which:

FIG. 1 is an exploded side view showing the components of a basic unit;

FIG. 2 is a side view of the assembled unit; and

FIG. 3 is a side view of a column made from components of 10 units shown to a reduced scale.

Referring to the drawings each unit comprises a transparent plastics container 5, a lid 6, a post having a body portion 7 which is of constant cross-section throughout its length and is surmounted by a reduced diameter spigot 9, and 10 rings 8, preferably of plastics material. The rings are dimensioned so that they fit around the body portion of the post but can be easily removed and replaced. The post is provided with a blind bore 10 complementary to and at the opposite end of the post from the spigot 9. A similar bore 11 is provided in the lid 6. The length of the main large-diameter body portion of the post and the internal height of the container are both equal to the height of the 10 rings when stacked one on top of the other, and the rings are preferably all of different colours, the post and lid preferably both being of the same colour.

FIG. 3 shows a column consisting of ten posts connected end-to-end by means of the spigots 9 and bores 10 and encircled by 100 rings in 10 blocks 12 of different colours. Top and bottom end caps 13 are provided to keep the rings in place and enable the assembly to stand upright or lie horizontally. The 10 posts are preferably of different colours each post corresponding in colour to the colour of its 10 associated rings. As mentioned above the lids 6 and post 7 of each unit are of the same colour and 10 units having posts of the desired colour can thus be readily selected by reference to the lids.

The device assists in number learning and basic arithmetic by the association of colours with numbers. The different colours on the column guide the child as to which colour of ring to place next on the column and

once each colour on the column is hidden by rings of that colour, 10 rings of that colour have been counted. The completed column will consist of 10 blocks of different colours, with the whole assembly representing

5 100, each block of colour representing 10 and each ring representing one. It will be appreciated that if the column is regarded as 10 and each block as one, then each ring will be 0.1 thereby facilitating teaching of the decimal system. The plastics containers 5 can be used as desired to "measure out" lots of 10 rings.

Apart from the above described basic function, the device can be used to teach basic addition and subtraction and the rings can be used quite separately if desired. Various number games and simple multiplication 15 and division can also be dealt with and this ability together with the colourful nature of the device renders it suitable as an educational toy for use in the home quite apart from its teaching functions in the classroom.

20 It should be appreciated that the device can be sold as a complete outfit rather than in separate units as described above or the rings in the units could all be of one colour. The posts forming the central column could all be the same colour if desired, though the device is believed to be more effective when the posts are

25 coloured to correspond to their associated rings. By forming the "hundred" column in sections from the ten posts a further counting aid is built-in to the device, but again a single post of the required length, either multi-coloured or of one colour, could be provided alternatively if desired. In a further alternative applicable to the arrangement using ten posts to form the column, the blind bore 10 shown in the drawings may be replaced by a bore extending completely through the post

30 which is thus of tubular form but still having different outer diameters at the portions 7 and 9, the former being dimensioned to fit into the bore. An advantage of the device is its relatively small size when assembled enabling it to remain erected when not in use.

40 It should be appreciated that the term "ring" used herein is intended to cover square, hexagonal, octagonal and other ring shapes apart from circular.

We claim:

45 1. An educational device or toy comprising a post, a plurality of rings of equal size which fit around the post, the post having a body member of constant cross-section and of a length such that when 10 rings are fitted round the post and supported one upon another they enclose the body member throughout its length, attachment means enabling the post to be connected to another similar post in end-to-end relation with their body members in abutment with one another, and a transparent container equal in internal height to the body member of the post.

50 2. An educational device or toy according to claim 1 wherein said attachment means comprises a spigot at one end of said post and a complementary bore at the other end of said post, said container being provided with a lid having a bore engageable with said spigot.

55 3. An educational device or toy according to claim 2 wherein said lid and said post are the same color.

60 4. An educational device or toy comprising a post, a plurality of rings of equal size which fit around the post, the post having a body member of constant cross-section and of a length such that when ten rings are fitted round the post and supported one upon another they enclose the body member throughout its length,

attachment means enabling the post to be connected to another similar post in end-to-end relation with their body members in abutment with one another, said attachment means including a spigot at one end of said post and a complementary bore at the other end of said post, and at least one container equal in internal height to the body member of the post, the container being provided with a lid having a bore engageable with the spigot.

5. An educational device or toy according to claim 4 wherein said lid and said post are the same color.

6. An educational device or toy comprising 10 units each consisting of a transparent container in which is

a post having a body portion of constant cross-section throughout its length and equal in height to the container, and 10 rings disposed one upon another to surround the body portion of the post throughout its length, each container having a lid of the same colour as its post and rings, all ten lids being of different colours and the posts having attachment means enabling them to fit together end-to-end with their body portions in abutment to form a column having ten equal differently coloured sections and capable of accommodating exactly 100 rings.
